WITNESS:

UNITED STATES PATENT OFFICE.

HENRY J. SCHMOLL, OF RACINE, WISCONSIN.

CALF-WEANER.

1,382,555.

Specification of Letters Patent. Patented June 21, 1921.

Application filed December 28, 1920. Serial No. 433,600.

To all whom it may concern:

Be it known that I, HENRY J. SCHMOLL, a citizen of the United States, residing at Racine, in the county of Racine and State 5 of Wisconsin, have invented new and useful Improvements in Calf-Weaners, of which the following is a specification.

This invention relates to calf weaners and has for its object the provision of a device 10 adapted to be engaged upon the nose of a calf and to hang down over its mouth so as to frustrate efforts of the calf to suck a cow but which will not interfere with drinking or grazing, the plate member which 15 depends from the mouth being swingable upwardly in the act of grazing.

An important object is the provision of a device of this character which includes a pair of separable members engageable within 20 the nostrils of a calf and having a dove-tailed connection with each other, these members being locked against separation by means carried by the plate depending in front of the mouth.

Another object is the provision of a device of this character in which the nostril engaging members are formed with ring portions through which an operator may 25 insert his thumb and first finger for holding these members in position prior to locking them together by means on the plate, the device entirely avoiding the use of bolts, rivets, cotter pins, or any other similar fastening devices.

An additional object is the provision of a device of this character which will be simple and inexpensive in manufacture, easy to apply even to a rather vicious calf, which will be highly efficient and durable in use, 30 and a general improvement in the art.

With the above and other objects and advantages in view, the invention consists in the details of construction to be herein-after more fully described and claimed and 35 illustrated in the accompanying drawings in which—

Figure 1 is a perspective view showing my device in position upon a calf.

Fig. 2 is a side elevation of the device 40 applied and showing it in the position assumed when the calf is grazing,

Fig. 3 is an elevation of the device on a larger scale than that of Fig. 1,

Fig. 4 is a central cross sectional view, 45

Fig. 5 is a detail cross sectional view through the nose engaging members taken

along the hole through which the locking hook passes,

Fig. 6 is a similar view taken above the line of Fig. 4, and 60

Fig. 7 is a perspective view of the nose engaging members separated.

Referring more particularly to the drawings, I have shown my device as comprising a nose engaging portion designated broadly 65 by the numeral 10, and a guard plate 11. This nose engaging portion is formed of two sections 12 which are readily separable and each of which includes a hook 13 having a knob-like end 14 for engagement within 70 the nostril of a calf. Formed integrally with the lower end of the hook portion is a rectangular plate 15 which is of only one-half the thickness of the hook portion, as clearly shown, so that when the two sections 75 are properly assembled the sides of the plate portion 15 will be flush with the sides of the hook. These plate portions 15 are connected with the hook portions by relatively small necks 16 and the free edge of each 80 plate portion is formed with a notch 17 for engagement upon the neck of the other plate and the edges of these necks and of the notches are correspondingly beveled, as shown at 18 and 19, respectively, so that 85 the elements will have a dove-tailed fit. The upper and lower edges of the plate members 15 are also preferably beveled or rounded, as shown at 20, to avoid sharp edges. The portions of the hooks at the 90 sides of the neck 16 are likewise beveled, as shown at 21, for conforming engagement with the beveled free edges 22 of the plate portions 15 so that there will be interfitting relation of these parts so as to brace the 95 structure efficiently.

Formed integrally upon the hooks 13 are laterally extending ring members 23 designed for the passage of the thumb and forefinger of the operator to facilitate placing 100 the device upon the nose of the calf.

In order to lock the sections 12 against casual separation, the plate portions 15 are formed with rectangular openings 24 which register when the sections are assembled and 105 which are designed to receive a hook 25 formed upon a relatively large guard plate 26. This guard plate is preferably rounded at all its edges so as to avoid sharp corners and may be formed with a plurality of openings 27 for the purpose of reducing its weight. This guard plate is formed cen-

trally of its upper portion with a rectangular opening 28 for the accommodation of the lower portion of the assembled sections 12 so as to permit engagement of the hook 25 within the openings 24. The upper part of this opening 28 is spanned by a rearwardly offset web 29 from the lower edge of which extends the hook 25 and it will be observed that this hook is of compound curvature so as to provide a retaining portion 30 which serves as more or less of a pivot for the nose engaging sections 12. The engagement of the plate portions 15 of the assembled sections 12 with the web 29, however, prevents swinging movement of the guard plate with respect to the nose engaging section in one direction.

The use of the device is as follows:

In the first place the guard plate 11 is disengaged from the sections 12 and the sections 12 are separated. The operator then places his thumb and forefinger through the rings 23 of the sections 12 so as to hold them properly and then inserts the knob 14 with 25 in the nostrils of the calf to be weaned. He then brings the sections 12 into such position that the plate portions 15 thereof will lie against each other and he then presses the sections together to slide these plate portions 30 one upon the other to engage the notches 17 over the neck portions 16. Owing to the beveling of the interfitting edges of these sections it will be seen that they will be held firmly against relative lateral displacement. 35 The operator then grasps the guard plate 11, inserts the hook 25 thereof within the registering holes 24. When the device is thus placed upon an animal it will be seen that if any attempt is made to suck the guard plate 40 11 will be very much in the way and will prevent the calf from getting a teat within his mouth. This action occurs because when the sections 12 are swung into the position necessary for admitting sucking the engagement thereof with the web 29 will cause the guard plate and sections 12 to extend in the same plane. It is, however, to be noted that the guard plate 11 will swing out of the way 45 if the calf desires to drink or graze as the

curving of the retaining portion 30 of the hook is such as to permit limited pivotal movement of the guard plate with respect to the nose engaging members.

While I have shown and described the preferred embodiment of my invention, it is of course to be understood that I reserve the right to make such changes in the form, construction, and arrangement of parts as will not depart from the spirit of the invention or the scope of the subjoined claims.

Having thus described my invention, I claim:

1. A device of the character described comprising a nose engaging member including a pair of slidably engaged separable sections formed with mating openings, and a plate carrying a hook engageable through said openings.

2. A device of the character described comprising a nose engaging member including a pair of slidably associated separable sections each having a hook portion and a ring portion, the hook portions being engageable within the nostrils of a calf and the ring portions serving as handles or finger holds, said sections being formed with mating openings, and a guard plate carrying a hook engageable through said openings.

3. A device of the character described comprising a pair of similar slidably associated separable sections each formed as a hook engageable within a nostril of an animal and each including a ring portion formed on the hook and further including a plate portion connected with the lower end of the hook portion by a neck, the free edge of each plate portion being engaged and beveled for conforming engagement with the beveled edges of the other neck portion, and said plate portions being formed with registering holes, in combination with a guard plate formed with an opening for the accommodation of said plate members and carrying a hook at said opening for engagement within said registering openings.

In testimony whereof I affix my signature.

HENRY J. SCHMOLL.
